UNITED STATES PATENT OFFICE.

ARTHUR P. CODY, OF CLEVELAND, OHIO.

BATH-ROOM FIXTURE.

1,312,613.

Specification of Letters Patent. Patented Aug. 12, 1919.

Application filed November 1, 1918. Serial No. 260,744.

To all whom it may concern:

Be it known that I, ARTHUR P. CODY, a citizen of the United States, residing at Cleveland, in the county of Cuyahoga and State of Ohio, have invented a new and useful Bath-Room Fixture, of which the following is a specification.

This invention relates to bath room fixtures, the object being to effect a combination construction of an ordinary bath tub and a lavatory basin, the said combination being designed for use in bath rooms where the space is limited.

Another object is to arrange the combination so that one pair of water faucets may be employed for both the lavatory basin and the tub.

Another object is to arrange the waste pipe of the basin so as to bring it within the bath tub and thus eliminate the necessity of two waste pipes.

Another object is to mount the wash basin rotatably so that it can be swung out of the way in order to permit the use of the tub.

Another object is to provide a spring locking device that will secure the basin in position beneath the spigot or in inoperative position when the tub is to be used.

With these objects in view the invention consists in the novel construction and arrangement of parts, hereinafter described, illustrated in the accompanying drawings, and particularly pointed out in the appended claims, it being understood that various changes in the form, proportions, size and minor details of construction may be made within the scope of the appended claims, without departing from the spirit or sacrificing any of the advantages of the invention.

In the drawings:

Figure 1 is a plan view of my improved combination bath room fixture, with the basin shown in full lines in position to be used and in dot and dash lines in the position which it will assume when the use of the bath tub is desired.

Fig. 2 is a side elevation partly in section of my device.

Fig. 3 is a fragmentary end view.

Fig. 4 is an enlarged section on the line 4—4, Fig. 2 looking in the direction indicated by the arrows.

Fig. 5 is a sectional view taken on line 5—5, Fig. 4.

Similar numerals of reference indicate

corresponding parts throughout the several figures of the drawings.

1 indicates an enameled bath tub of ordinary and well known construction. The usual pipes 2 for hot and cold water and the usual apertures indicated at 4, through which the water pipes are designed to enter the tub are provided, but the pipes do not, however, enter the tub through these apertures but extend a predetermined distance above the top rim of the tub and are then bent inwardly toward the tub and equipped with the usual spigot or spigots 5, the said spigots being arranged in alinement inside the end wall of the tub. A bracket 6 is secured through the apertures 4 to the end wall of the tub and carries a clamping member which is fastened to the water pipes and acts as a support for them. Secured to each of the water pipes 2 at a point slightly below the inturned portion of the said pipes, is an annular collar 7, the said collars being in horizontal alinement with each other and secured upon the said pipes by means of set screws 8. An annular ring 9 rests upon the collars 7 and inwardly extending enlarged portions 10 formed at diametrically opposite sides of said ring are provided with central apertures 11 through which the pipes 2 are designed to extend. An annular groove 14 is formed upon the exterior of the ring member 9 and seated within the said groove is a split ring, the members 15 and 16 of which are provided with ears 17 through which extend bolts 18 to secure the said split ring together in position within the groove. Formed integral with the member 16 of the split ring is a substantially square extension 19 with a depending rounded portion 20 in which is formed a lateral groove 21. Adjacent either end of the enlarged portion is a threaded aperture in which is fitted a set screw 22. A flange 24 of a lavatory basin 25 is seated within the groove formed in the enlarged portion and secured therein by the set screws 22. The split ring is rotatably mounted within the groove 14 thus permitting the basin to be swung into the full line position shown in Fig. 1 or backwardly in the dotted line position shown in this figure. A waste pipe 26 is connected to the basin and extends downwardly and discharges within the tub, the said waste pipe being off-set as clearly shown in Fig. 3 to permit the basin to be swung backwardly when the use of the tub is desired.

A leaf spring 27 is fastened to the upper face of the ring 9 by one of its ends, the opposite end of the said leaf spring projecting over the periphery of the ring 9 and having secured therein a depending pin 28 and a knob 29. An aperture 30 is formed in the member 15 and is designed to receive the pin 28 when the basin is swung forward in position to be used. When the pin 28 is seated in the aperture 30, as just described, the split ring is locked against rotation within the groove 14 but when it is desired to swing the basin back, the pin can be removed from the aperture 30 by means of the knob 29 and the basin rotated into inoperative position when a second aperture 31 will be brought into alignment beneath the pin 28 and when the knob 29 is released the pin will be seated in the aperture 31 and the parts once more locked against relative movement. The arrangement of the bath room will sometimes necessitate the basin being swung forwardly instead of backwardly when use of the bath tub is desired and in this case the drain pipe 26 can be turned a half of a revolution to extend backwardly from the basin and an aperture 32 for the pin 2 is provided in the split ring to lock the basin in inoperative position.

From the foregoing it will be obvious that with the use of my combined bath room fixture a very compact arrangement of the bath tub and lavatory basin can be made, only one set of water pipes and spigots being necessary for the tub and the basin. With my combination fixture but one drain pipe is necessary for both the tub and basin, thus eliminating a considerable amount of labor and piping in installing the fixture. A considerable amount of space is likewise saved and a big advantage thus gained in bath rooms where space is limited.

Having fully described my invention what I claim as new, is—

1. A bath room fixture comprising a stationary tub, water pipes adjacent said tub, spigots upon said pipes arranged above said tub, a grooved ring carried by said pipes and a basin rotatably mounted upon said grooved ring, the said basin being designed to be rotated upon said ring and brought into position beneath said spigots when said basin is to be used and swung backwardly from beneath said spigots when said tub is to be used, means for locking the basin in

either position and a waste pipe from said basin arranged to discharge within the said tub.

2. A bath room fixture comprising a tub, water pipes for supplying water to said tub, the outlets to said pipes being arranged above said tub, a basin rotatably mounted upon said pipes and designed to be swung into position beneath said outlets and a waste pipe from said basin extending to a point adjacent the bottom of said tub.

3. A bath room fixture comprising a stationary tub, water pipes adjacent said tub, a grooved ring carried by said pipes and a basin rotatably mounted upon said grooved ring.

4. A bath room fixture comprising a tub, water pipes adjacent said tub, a grooved ring carried by said pipes and a basin rotatably mounted upon said ring, above said tub.

5. A bath room fixture comprising a tub, a plurality of water pipes arranged to admit water to said tub, spigots upon said pipes above said tub, a grooved ring upon said pipes and a basin rotatably mounted upon said ring and arranged to be moved into position beneath said spigots and to be swung backwardly from beneath said spigots.

6. A bath room fixture comprising a tub, water pipes for supplying water to said tub, a grooved ring carried by said pipes, a basin rotatably mounted upon said ring and designed to be swung beneath the outlets of said pipes, means for locking the basin in position beneath said outlets and a waste pipe from said basin extending to a point adjacent the bottom of said tub.

7. A bath room fixture comprising a stationary tub, water pipes adjacent said tub, spigots upon said pipes arranged above said tub, a grooved ring carried by said pipes, and a basin rotatably mounted upon said grooved ring, the said basin being designed to be rotated upon said ring and brought into position beneath said spigots when said basin is to be used and swung backwardly from beneath said spigots when the tub is to be used and a waste pipe from said basin arranged to discharge within the tub.

In testimony that I claim the above, I have hereunto subscribed my name.

ARTHUR P. CODY.
